SWEETENING HYDROCARBON OILS

Application filed April 25, 1927. Serial No. 186,276.

This invention relates to the sweetening of hydrocarbon oils and particularly petroleum distillate such as gasoline and kerosene.

The invention will be readily understood from the following description of a preferred method of sweetening gasoline in accordance therewith.

The accompanying drawing illustrates diagrammatically a suitable apparatus for this purpose.

Referring to the drawing, 10 is a line for supplying gasoline to be treated. The line 10 connects with the suction side of a pump 11, the pressure side of which is connected by pipe 12 to a suitable mixer 13, shown by way of example as a chamber with numerous baffle plates 14. A pipe 15 connects with the pipe 12 for the purpose of supplying doctor (the usual sodium plumbite treating solution) thereto from the doctor receiving vessel 16. From the mixer 13 a pipe 17 leads to a settling chamber 18 which is of such size that substantially all the sodium plumbite sludge settles out of the gasoline therein, together with more or less lead sulfide produced by the interaction of sulfur compounds of the gasoline with the doctor. The chamber 18 is preferably provided with a gauge glass 19. From the base of the settling chamber 18 a valved pipe 20 leads to the vessel 21. From the top of the chamber 18, a pipe 22 leads to a mixer 23 which may be similar to the mixer 13. The pipe 22 is provided with means for supplying sulfur in reactive form thereto, for example, a pipe 24 may be provided which communicates with pipe 22, for the purpose of supplying gasoline saturated with sulfur in the quantity necessary to decompose the lead compounds retained by the plumbite treated gasoline. From the mixer 23 a pipe 25 leads to a settling chamber 26 which is of such size that substantially all the lead sulfide which is carried over by the gasoline from settling chamber 18 and which is produced by the reaction of the sulfur introduced by pipe 24 upon the lead compounds retained by the plumbite treated gasoline, is precipitated therein. From the top of chamber 26 a pipe 27 leads the treated gasoline to storage. From the bottom of the chamber 26 a pipe 28

leads to a reaction vessel 29, a pump 30 being provided in the pipe 28. Pipes 31, 32, and 33 are adapted to supply sulfuric acid, water and sodium hydroxide solution to the vessel 29. The vessel 29 is provided near its base with a valved liquid draw-off pipe 34 and at its base with a pipe 35 which leads to the doctor receiving vessel 16. The vessel 16 is preferably at a lower level than vessel 29 so that liquid may flow from the latter to the former vessel through pipe 35 by gravity. In the lower portion of vessel 29 are located perforated coils or pipes 36 and 37 connected with pipes 38 and 39 respectively for supplying air and steam into the liquid in the vessel 29. From the vessel 21 a valved pipe 40 leads to the vessel 29. The vessel 21 is preferably at a higher level than the vessel 29, so that liquid may flow from the former to the latter by gravity. From the base of vessel 16 a pipe 41 leads to a pump 42, the outlet of which is connected with the pipe 15. A pipe 43 connects with the pipe 15 for the purpose of supplying fresh doctor thereto.

The operation is as follows. Gasoline to be sweetened is supplied by pipe 10 to the pump 11 which forces it through pipe 12. Doctor is drawn from vessel 16 and supplied by pump 42 through pipe 15 to pipe 12, the proportions of doctor and gasoline being controlled by the rate of operation of these pumps. The gasoline and doctor are intimately contacted by passage through the mixer 13 so as to ensure thorough reaction between the doctor and the sulfur compounds of the gasoline. The thoroughly mixed gasoline and doctor pass by pipe 17 to the settling chamber 18 in which substantially all the aqueous solution settles out. The gasoline which constitutes the upper layer in settling chamber 18, together with some lead sulfide suspended therein passes through pipe 22 and gasoline containing sulfur in solution is supplied by pipe 24 in such quantity that the sulfur content will react with the lead compounds in the gasoline to yield sweet gasoline. The gasoline from pipes 22 and 24 is thoroughly mixed in mixer 23 and the mixture then passes to the settling chamber 26, lead sulfide precipitates in the chamber 26, 100

and the treated gasoline passes by pipe 27 to storage.

When a quantity of lead sulfide has accumulated in chamber 26, it is pumped through pipe 28 to the reaction vessel 29. Concentrated sulfuric acid, suitably 98% acid, is supplied by pipe 31 and the mixture agitated by introducing air by pipe 38 and perforated coil 36. Agitation may be effected in any other suitable manner, if desired. The lead sulfide is thereby converted into lead sulfate as follows:

15 The reaction is ordinarily completed in about two hours. The sulfate is then allowed to settle and excess acid is drawn off by pipe 34. Water is now supplied to the vessel 29 by pipe 32 and the sulfate is washed with the 20 water while agitating by air from the pipe 38. The sulfate is allowed to settle and the water drawn off by pipe 34. This operation may be repeated if necessary until the sulfate retains only a small amount of acid.

25 The spent doctor, rich in sodium hydroxide and low in lead, which settles out in chamber 18 may be withdrawn intermittently or continuously to the vessel 21. From the vessel 21 this liquid is led by pipe 40 to the reaction 30 vessel 29 where it is mixed with the washed lead sulfate, the production of which has been hereinbefore described. The mixture is agitated with air and steam introduced by pipes 38 and 39, for about one hour, until the solution is saturated with lead. The reaction may 35 be expressed as follows:

40 Since a certain quantity of the sodium hydroxide is converted into sodium sulfate which is inert in the purification of the oil, an equivalent amount of sodium hydroxide may be introduced by pipe 33 to enable the 45 desired lead content to be held in solution. The doctor thus produced is passed by pipe 35 to the doctor receiving vessel 16 from which it is withdrawn for use by the pipe 41. Additional doctor is introduced into the system 50 by pipe 43 whenever necessary.

It must be understood that the foregoing description of the purification of gasoline is illustrative only and that the invention is not limited thereto except by the terms of the 55 appended claims.

We claim:

1. The method of sweetening hydrocarbon oils with doctor and reactivating the partially exhausted doctor resulting from such 60 sweetening operation which consists in treating said oil with doctor, separating partially exhausted doctor therefrom, subsequently precipitating substantially anhydrous lead sulfide from the oil, converting said lead sulfide into lead sulfate and dissolving said 65

sulfate in the partially exhausted doctor solution thereby converting it into active plumbite.

2. The method of sweetening hydrocarbon oils with doctor and producing doctor from 70 the partially exhausted doctor resulting from such sweetening operation which consists in treating said oil with doctor, separating partially exhausted doctor therefrom, subsequently adding sulfur to said oil and separating lead sulfide therefrom, converting said sulfide into sulfate, and dissolving said sulfate in caustic soda to produce doctor.

3. The method of sweetening hydrocarbon oil distillate which consists in treating said oil distillate with doctor, separating spent doctor of reduced lead and increased alkali content therefrom, subsequently precipitating anhydrous lead sulfide from said distillate, treating said sulfide with sulfuric acid to 80 convert it into lead sulfate, dissolving said sulfate in said spent doctor to replenish the lead content thereof, and reutilizing the doctor for the sweetening of distillate.

4. The method of sweetening hydrocarbon oils, which consists in treating said oil with doctor, separating partially exhausted doctor, together with lead sulfide, therefrom, subsequently precipitating substantially anhydrous lead sulfide from the oil, converting said substantially anhydrous lead sulfide into lead sulfate, dissolving said sulfate in said partially exhausted doctor solution, thereby converting it into active plumbite, and reusing the resulting doctor solution containing lead sulfide in the sweetening of hydrocarbon oils.

5. The method of sweetening hydrocarbon oils, which consists in treating said oil with doctor, separating partially exhausted doctor, together with lead sulfide, therefrom, subsequently adding sulfur to said oil and separating lead sulfide therefrom, converting last said sulfide into sulfate, dissolving said sulfate in the partially exhausted doctor solution, thereby converting it into active plumbite, and re-using the resulting doctor solution containing lead sulfide in the sweetening of hydrocarbon oils.
